UNITED STATES PATENT OFFICE.

OLOF SWANSON, OF DENVER, COLORADO.

LUBRICATOR

1,279,173.

Specification of Letters Patent. Patented Sept. 17, 1918.

Application filed October 19, 1917. Serial No. 197,420.

To all whom it may concern:

Be it known that I, OLOF SWANSON, a citizen of the United States, and a resident of Denver, Colorado, have invented a certain new and useful Improvement in Lubricators, of which the following is a full, clear, and exact description.

My invention is an improvement in lubricators and relates in particular to certain improvements adapted particularly to flange lubricators of the type illustrated and claimed in my Patent No. 1,229,822, issued June 12, 1917. The principal objects of my invention are the provision of a lubricator having a feed regulator (as distinguished from a regulating valve) controlled and operated by vibration transmitted thereto on account of the lateral movement of the wheels with respect to the engine or car frame; to associate with such feed regulator a feed controlling valve automatically operated by the same vibration and constructed to positively close and shut off feed of the lubricant when the engine is standing still; and to provide certain other improvements in detail of construction and simplicity of parts which will later appear from this specification.

In the single sheet of drawings accompanying this application and forming a part hereof—

Figure 1 is a partial, central, vertical section and partial side elevation illustrating my device and the manner of supporting and utilizing the same; and

Fig. 2 is a partial horizontal section and partial plan view showing details of the mounting of my device.

Referring to the drawings, in which like characters of reference indicate like parts in the several views, let 1 designate the lubricant container which is preferably of cylindrical shape with a reduced lower extremity 2, also of cylindrical shape. A spring pressed cover 3 pivoted on the pin 4, held in ears 5, closes the upper end of the container and a plug 6 is threaded into the lower end of the container portion 2, to provide a readily accessible means for cleaning. In one side wall of the reduced lower portion 2 of the container there is formed a port 7 which communicates with a downwardly inclined chamber 8 preferably formed integrally with the container by casting the entire device.

The lower end of the chamber 8 is inter-

riorly threaded as indicated in the drawings and a lubricant distributing nozzle is screwed therein. This nozzle is preferably a chilled casting having a cylindrical opening or bore cored throughout its length, said bore being of greater diameter toward the surface 10 which is to engage the flange 11 of the wheel W. Within the bore in the nozzle 9 I place a pin 12, this pin being of considerably less diameter than the lower end of the bore but of only slightly less diameter than the upper or inner portion of the bore. A flattened head 13 serves to prevent the pin 12 from falling out of its socket.

At one side of the reduced lower portion 2 of the lubricant container I locate a heating chamber in as close proximity as possible to the lubricant regulator and controlling parts. This chamber 14 is provided with a pipe 15 leading thereto from the exhaust of the air pump or like source to furnish expanded steam to the chamber 14. Here the steam condenses, delivering heat at moderate temperature to the container adjacent thereto and maintaining the lubricant fluid even in the coldest weather. The water of condensation accumulates in the lower portion of the chamber until it rises high enough to run out the downwardly inclined escape 15, a limited excess of water from which may trickle past the pin 16, which substantially but not quite fills the bore of an opening in the plug 17 which closes the lower end of the escape 15. This construction provides a very restricted opening out of the chamber 14, thus preventing the rapid escape of steam; and the pin 16, which is free to travel a short distance in its bore, prevents the accumulation of dirt to clog the restricted opening. A screw plug 18 closes the cleaning port in the chamber 14.

In the upper end of the reduced portion 2 of the lubricant container there is screwed a valve cage 20, closed at its lower end save for a restricted port 21 and provided on its lower face with a hexagonal wrench engaging face 22. The cage 20 is screwed up in its socket until its shoulder 33 engages a similar shoulder formed on the container; the plug is now home with its lower face well above the port 7. Around the upper reduced end of the cage 20 and resting on a shoulder 23 thereon, there is mounted a screen 24 through which the oil passes in leaving the main reservoir in the container.

The lower end of the hollow in the cage 20 slopes downward toward the port 21 and a ball 25 rests on said sloping surface and normally closes the port 21.

5 A split sleeve 26 surrounds the container 1 at an appreciable distance above the center of gravity of the device and this sleeve carries a trunnion 27. A bearing 28 supports the trunnion in such manner that the 10 same is free to turn therein, and the bearing 28 is carried by a sleeve 29 and stands with its axis at right angles to the axis of said sleeve. This sleeve 29 is split and is adapted to be mounted in any desired position 15 on a cylindrical bracket 32 by means of a nut 30 passing through the ears 31 on the sleeve sections. The bracket 32 is secured by bolts 36 to any convenient frame portion 37 of the rolling stock on which 20 the device is to be used.

As shown and claimed in my Patent No. 1,229,822 mentioned, a spring 34 held between the bearing 28 and a collar 35 pinned to the end of the trunnion 27 permits movement 25 of the trunnion longitudinally of the bearing 28 but resists such movement.

Mounting and operation.

The bracket 32 is preferably so mounted 30 on the frame 37 of the engine or car to which the device is to be applied that the bracket stands between the lubricator and the wheel. The container 1 is supported by the collar 26 with its center of gravity below 35 the collar and the sleeve 29 is so located on the bracket 32 that the surface 10 on the nozzle rests lightly against the flange 11 of the wheel W; and the nozzle will tend to follow the flange on account of the eccentricity 40 of the trunnion 27. If in use any play develops in any of the bearings of the device the tendency will be for the surface 10 to crowd toward the angle formed by the tread and flange of the wheel.

45 The lateral movements of the wheel W with reference to the frame of the engine or car are sudden and the effect is that of striking the nozzle 9 a blow whose vibrations are transmitted throughout the device; one 50 result of this blow is the imparting of a travel to the pin 12 with reference to its cavity or bore. The space between the pin 12 and the upper or reduced portion of its bore is extremely restricted; it may be described as sufficient to permit of a very slight trickling of the lubricant around the pin if the lubricant is very fluid and the valve proper is open—even when the pin is not vibrated. Under the same conditions 55 otherwise but with a stiff lubricant none would flow around the pin. But when the pin 12 is vibrated in the manner described the feeding will be much accelerated and the rate of its increase will be in proportion 60 to the amount of vibration imparted to the

pin. The pin 12 and its bore thus constitute a "regulator" but in no sense form a valve; this regulator acts to allow a certain amount of lubricant to pass under a given amount of vibration. If it be determined 70 that a certain amount of a certain kind of lubricant is best, this result may be obtained by proportioning the pin to the bore; and then the desired amount of feeding will always result. 75

The vibration imparted to the container by the described blows of the wheel W will cause the ball 25 to repeatedly leave its seat and permit lubricant to be fed downward through the port 21. As soon as the chamber below the cage 20 is filled this lubricant will overflow through the port 7 and be fed downward around the pin 12 as described. After passing through the more restricted portion of the bore of the nozzle, the lubricant 85 falls into the larger bore of the cavity where it runs down readily to the surface 10 from whence it is distributed on the wheel flange.

The inclination given the seat of the ball 25 is slight enough to permit ready response of the ball to the vibrations described and still there is sufficient inclination given the same so that the ball will return by gravity to close the port 21 even if the engine or 95 car be stopped on a curve and therefore stand tilted.

From the foregoing description it will be clear that I have produced a combination in which the feed of oil is regulated by a device agitated in proportion to the speed of travel of the rolling stock and in which there is a valve back of the regulator to govern the feed to the regulator and shut the same off automatically as soon as the engine is not running. When the valve 25 is closed discharge of oil from the nozzle ceases on account of atmospheric pressure.

Devices such as shown in my patent mentioned where a single valve is operated by the vibration described are operative but are rather delicate for working conditions; and if they happen to stick in open position the lubricant will waste. The devices shown in the present application have been found to be reliable and durable in use and not to get out of order.

I find the form of cavity shown for the pin 12 to be desirable for the reason that the restricted portion is long enough to accurately gage the flow around the pin and it is better to have a larger bore adjacent the discharge end so that particles of metal and dirt which enter the same may not clog the discharge but may be worked out by the reciprocation of the pin 12. By the form given my device illustrated in the drawings three different spaces are provided for the collection of sediment from the lubricant; the first is around the upper reduced end of 125

the cage 20 where it projects above the adjacent inclined sides of the container; the second is in that portion of the container portion 2 which is above the plug 6 and below the port 7; and the third is in the angle between the lower side of 8 and the inner end of 9 below the bore therethrough.

If it is found that on account of excessive knocking in the journal boxes the nozzle 9 ever flies out so far as to ride on the rim of the flange 11 this can be readily remedied by mounting an adjustable, rigid finger either on the bracket 32 or on some part of the frame, which shall overlie the nozzle 9 and prevent its moving a sufficient distance radially of the wheel to engage the rim of the flange.

Having thus described my invention, what I claim and desire to secure by Letters Patent is:—

1. In a lubricator, a nozzle having a longitudinal bore therethrough, said bore having a relatively large diameter section adjacent its outer end, and a relatively small diameter section adjacent its inner end, a pin within said bore, said pin and the small diameter section of said bore being so proportioned that the pin approximately stops the flow of lubricant through the small bore section while the pin is quiet but induces and regulates a substantial flow therethrough when said pin is in vibration, and means for supplying a lubricant to the inner end of said nozzle.
2. A lubricator comprising a lubricant container, a discharge nozzle connected therewith, a vibration actuated valve controlling feed from said container to said nozzle and a vibration actuated feed regulator in said nozzle.

3. A lubricator comprising a lubricant container having a bottom sloping toward a centrally located port, a ball normally closing said port but adapted to be displaced therefrom by vibration, a nozzle in communication with said port, and a vibration actuated feed regulator in said nozzle.

4. A lubricator comprising a lubricant container having a bottom sloping toward a centrally located port, a ball normally closing said port but adapted to be displaced therefrom by vibration, a nozzle in communication with said port, said nozzle having a longitudinal bore, and a pin within said bore, said bore and pin being so proportioned that the pin approximately stops the flow of lubricant through the bore while the pin is quiet but induces and regulates a substantial flow therethrough when said pin is in vibration.

5. A lubricator comprising a lubricant container, a discharge nozzle connected therewith, said nozzle having a longitudinal bore therethrough, a vibration actuated valve controlling feed from said container to said nozzle, and a pin in the bore of said nozzle, said bore and pin being so proportioned that the pin approximately stops the flow of lubricant through the bore while the pin is quiet but induces and regulates a substantial flow therethrough when said pin is in vibration.

6. In a lubricator, a heating chamber, means for supplying steam thereto, a water discharge port leading from said heating chamber, and a pin free to vibrate in said port.

In testimony whereof, I have hereunto affixed my signature.

OLOF SWANSON.
